UNITED STATES PATENT OFFICE.

MAX HERSKOVITZ, OF CHICAGO, ILLINOIS, ASSIGNOR TO PEERLESS LIGHT COMPANY, OF CHICAGO, ILLINOIS, A CORPORATION OF MAINE.

CURRENT-TAP SOCKET.

Application filed June 28, 1923. Serial No. 648,227.

To all whom it may concern:

Be it known that I, MAX HERSKOVITZ, a citizen of the United States, residing at Chicago, in the county of Cook and State 5 of Illinois, have invented a new and useful Improvement in Current-Tap Sockets, of which the following is a specification.

My invention relates, more particularly, to current-tap sockets adapted for the attachment thereto of a plurality of plugs, one 10 of which is of the push type, as distinguished from the more common form of threaded plug.

My primary object is to provide a novel, 15 simple and inexpensive construction of socket and one which shall be very strong and durable and present the desired appearance.

Referring to the accompanying drawing: 20 Figure 1 is a view in side elevation of my improved socket. Figure 2 is a plan view thereof. Figure 3 is a longitudinal section taken at the line 3 on Fig. 2 and viewed in the direction of the arrow. Figure 25 4 is a plan view of a portion of the interior of the socket structure; and Figure 5, a section taken at the line 5 on Fig. 3 and viewed in the direction of the arrow.

The particular construction shown comprises 30 a tubular member 6 preferably formed of relatively thin metal, with its opposite ends spirally corrugated to form the threaded portions 7 and 8, the portions 7 constituting a plug portion at which the 35 socket is adapted to screw into an ordinary threaded electric socket, the threaded portion 8 of the tube 6 constituting a threaded socket to receive an ordinary electric screw plug. The plug portion 7 is apertured at 40 its end wall, as represented at 9, in which aperture a disc 10 of insulating material is confined, this disc bearing at an annular flange 11 thereon, against the outer face of the said end wall. The disc 10 is provided 45 centrally with a metallic rivet 12 which constitutes the center contact of the plug portion of the socket structure, the other contact thereof being the shell 6. The socket portion 8 contains a disc 13 of current- 50 insulating material which seats against lugs 14 extending inwardly from the tube 6 and preferably formed by indenting the side wall thereof. The disc 13 carries the center contact 15 of the screw socket of the structure, this center contact being shown as

formed of a strip of metal 16 connected at one end with the rivet 12 and extending, at its opposite end, through a slot 17 in the disc 13, thence across the outer face of the disc, its extremity being formed with the 60 rearwardly-extending portion 18 which extends into another slot 19 in the disc 13, the strip 16 being so proportioned and arranged that the discs 10 and 13 will be rigidly held against the end wall of the plug portion 7 65 of the device and against the lugs 14, respectively, as shown in Fig. 3, it being noted that the two center contacts 12 and 15 are electrically connected together through the medium of the strip 16. The device also 70 comprises a socket member 20 for receiving a push plug, this socket member being represented at 20 and formed of a body of insulating material containing slots 21 extending 75 therethrough. The member 20 is formed at its inner face with a substantially 80 rectangular boss 22 which projects into and through a similarly shaped opening 23 in the side wall of the member 6 between the threaded portions 7 and 8 of the latter. 85 The member 20 contains a central opening 24 therein for receiving a screw 25 which passes through an opening 26 in a block 27 of insulating material hereinafter referred to, and screws into a threaded opening 28 85 in the strip 16. The contacts for the push socket are represented at 29 and 30, the contact 29 being preferably formed of metal to provide a curved portion 31 terminating in a flange 32, the member 29 being 90 rigidly secured, as, for example, by soldering it, to the wall of the opening 23 in the tube 6. The member 31 loops into the interior of the tube 6 through the opening 23, as shown, and its free, resilient, extremity 95 extends outwardly in the slot 21 of the member 20. The contact member 30 is secured, at a flange 33 thereon, to the strip 16, as by a rivet 34, thereby electrically connecting the contact 30 with this strip, and its free 100 extremity 35 extends outwardly in the slot 21 in the member 20.

The block 27 extends at its ends in diametrically-opposed slots 36 in the side wall of the member 6, the metal of the side wall, 105 in the forming of the slots 36, being preferably bent inwardly, as represented in Fig. 5, to form the upper and lower lips which oppose the opposite faces of the block 27. The parts are preferably so proportioned, as 110

shown, that the block 27 which flatwise engages the strip 16, as shown, bears at a side wall thereof against the inner face of the disc 13:

5 The tubular member 6 is surrounded, except for the plug end 7 thereof, by a housing 37 of insulating material which is preferably formed from a flexible sheet of such material, the sheet being rolled into substantially tubular form, with its free edges deflected to form radially-disposed, flatwise opposed flanges 38, the sheet forming the housing 37 being cut away at its flange-equipped portion, as represented at 39, to receive the 10 member 20. As will be noted, the outer end portion of the member 20 is of greater width than the portion 22, whereby this portion of greater width, and represented at 40, extends into overlapping relation to the ends of the 15 flanges 38 adjacent the member 20, the latter containing radially-disposed slots 41 into which these end portions of the flanges 38 extend in the assembled position of the parts, the member 40 thus operating to hold the 20 flanges closely together. If desired, the flanges 38 at the left hand end of Fig. 2, 25 may be connected together by any suitable fastening devices, as by the rivets represented at 42.

30 In the constructing of the device, it is preferred that the strip 16, discs 10 and 13 and tube 7 be first assembled to the position shown. The block 27 is then applied to position, and thereafter the housing 37 applied to encircling position on the tube 6. The member 20 is then applied to the position shown and rigidly held in place by applying the screw 28. It will be understood 35 from the foregoing that the structure provided is very simple, economical of manufacture, and very durable, the insulating block 27 not only serving to augment the rigidity afforded by the other parts but also serving to insulate the contact 29 from the 40 center contact strip 16.

45 The block 27 forms a support for the contact 29 bracing it against undue displacement in the inserting of the contacts of a plug into the openings 21 for engagement with the contacts 29 and 35.

50 While I have illustrated and described a particular construction embodying my invention, I do not wish to be understood as intending to limit it thereto as the same may 55 be variously modified and altered without departing from the spirit of my invention.

55 What I claim as new, and desire to secure by Letters Patent, is:

60 1. A device of the character described comprising a tubular member provided at its opposite ends with contacts, a strip member extending lengthwise of said tubular member and connecting together certain of said contacts, said tubular member containing 65 openings in its side wall, and a block of

insulating material extending crosswise of said tubular member in a plane parallel with said strip member, and extending at its ends into said openings.

2. A device of the character described comprising a tubular member provided at its opposite ends with contacts, members of insulating material located adjacent the ends of said tubular member, certain of said contacts being provided on said members of insulating material, a strip connecting said last referred to contacts together and holding said members of insulating material in assembled position, said tubular member containing openings in its side wall, and a block of insulating material opposing said strip and extending at its ends into said openings.

3. A device of the character described comprising a tubular member threaded at its opposite ends to afford a screw plug and a screw socket, respectively, discs of insulating material engaging said tubular member and held against movement toward each other, center contacts carried by said discs, a strip member connecting said center contacts together and holding said discs against movement in a direction away from each other, the side wall of said tubular member containing diametrically opposed slots and an opening located between said slots, a block of insulating material extending crosswise of said tubular member and opposing said strip, with its ends in said slots, a socket member located at said opening in said tubular member, a screw engaging said socket member and passing through said block and screwing into said strip, and contact members electrically connected with said tubular member and with said strip, extending into said socket member.

4. A device of the character described comprising a member provided with electric contacts certain of which extend laterally, a housing surrounding said member and open along its side, with its opposed edges outwardly flanged, said housing containing an opening in registration with said laterally extending contacts, and a plug co-operating with said last referred to contacts and containing slots into which the flanges on said housing extend.

5. A device of the character described comprising a tubular member containing openings in its side wall and provided with current-conducting members certain of which are connected together by a strip which extends lengthwise of said member, the side wall of said member containing an opening, a socket member located at said opening, a securing device engaging said member and said strip, and a block located in, and extending crosswise of, said member and supported at its ends by the latter, said block being interposed between said strip and said

socket member and against which said strip is drawn in the tightening up of said fastening devices.

6. A device of the character described comprising an integral tubular member threaded at its opposite ends, said member containing an opening in its side wall between said threads, a member of insulating material located adjacent said opening and containing slots, and contacts extending into a position to be engaged by the contacts of a push plug inserted into said slots.

7. A device of the character described comprising a tubular member threaded at its opposite ends, center contacts at the ends of said member and connected together, said tubular member containing an opening in its side wall, a member of insulating material located at said opening and containing slots, and contacts electrically connected with said tubular member and with said center contacts respectively, and extending into a position to be engaged by the contacts of a push plug inserted into said slots.

8. A device of the character described comprising a tubular member threaded at its opposite ends, center contacts at the ends of said member and connected together, said hollow member containing an opening in

its side wall, a member of insulating material located adjacent said opening and containing slots, contacts electrically connected with said tubular member and with said center contacts respectively, and an insulating block located in said tubular member and interposed between the part which connects said center contacts together and the one of said contacts which is connected with said tubular member and extends adjacent one of said slots.

9. A device of the character described comprising a tubular member threaded at its opposite ends, center contacts at the ends of said member and connected together, said member containing an opening in its side wall, a member of insulating material located adjacent said opening and containing slots, contacts electrically connected with said tubular member and with said center contacts respectively, the one of said contacts which is connected with said tubular member but bent into curved form with its extremity extending adjacent one of said slots and an insulating block in said tubular member interposed between said curved part of said contact and the part which connects said center contacts together.

MAX HERSKOVITZ.
